Irving W. Jorgensen, 800 River Bend Drive, R.R. 3,
Owosso, Mich.

Filed Mar. 7, 1962, Ser. No. 69,116

Term of patent 14 years

(Cl. D14—6)

FIG. 1 is a front elevational view of an insect deflector for automobile windshields showing my new design on a reduced scale;

FIGS. 2, 3 and 4 are top plan, front elevational and bottom plan views, respectively, of the insect deflector of FIGURE 1; and

FIG. 5 is a sectional view thereof taken on line 5—5 of FIG. 3.

The automobile fragmentarily shown in broken lines is included for illustrative purposes only.

I claim:

The ornamental design for an insect deflector for automobile windshields, substantially as shown and described.
